DESIGN FOR A TRACTOR

Robert G. Le Tourneau, Peoria, Ill., assignor to
R. G. Le Tourneau, Inc., a corporation

Application August 1, 1941, Serial No. 192,623

Term of patent 14 years

To all whom it may concern:

Be it known that I, Robert G. Le Tourneau, a citizen of the United States, residing at Peoria, in the county of Peoria and State of Illinois, have invented a new, original, and ornamental Design for a Tractor, of which the following is a specification, reference being had to the accompanying drawing, forming a part thereof.

In the drawing:

The side of the tractor opposite that shown in Fig. 1 presents substantially the same appearance as that depicted.

I claim:

The ornamental design for a tractor, as shown and described.

ROBERT G. LE TOURNEAU.
